TUBULAR-MAGAZINE AUTOMATIC FIREARM

Carl G. Swebilius, Hamden, Conn., assignor to
Western Cartridge Company, New Haven,
Conn., a corporation of Delaware

Application June 21, 1939, Serial No. 280,222

4 Claims. (Cl. 42—17)

This invention relates to improvements in tubular-magazine automatic firearms, that is to say, firearms having tubular-magazines and a construction and arrangement of parts whereby the discharge of one cartridge automatically effects the extraction and ejection of the just-fired cartridge and the insertion of a fresh cartridge into the cartridge-chamber of the firearm preparatory to another cycle of operation.

One of the objects of the present invention is to provide a superior tubular-magazine automatic firearm characterized by novel and superior cartridge-elevating means to thus insure the proper automatic feeding of a fresh cartridge into the cartridge-chamber of the firearm.

Another object of the present invention is to provide an automatic firearm of the type referred to in which reliable and effective means is provided for insuring the one-by-one feeding of a column of cartridges from a tubular-magazine for insertion into the cartridge-chamber of the firearm.

A further object of the present invention is to provide a superior tubular-magazine automatic firearm having a novel construction and arrangement of parts whereby the gases escaping rearwardly from the cartridge-chamber of the firearm when a just-fired cartridge is extracted, will be permitted to escape in a manner which will not tend to clog the tubular-magazine nor subject the marksman to discomfort.

Still another object is to provide a firearm of the character described, with superior, reliable and effective means for locking the firing-mechanism of the firearm against release.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of a tubular-magazine automatic firearm embodying the present invention;

Fig. 2 is a broken view in vertical central-longitudinal section and partly in side elevation, with the parts shown in the positions due to them at an instant prior to the discharge of the firearm;

Fig. 3 is a similar view but showing the breech-bolt in its fully retired position;

Fig. 4 is a transverse sectional view taken on the line 4—4 of Fig. 3;

Fig. 5 is a transverse sectional view taken on the line 5—5 of Fig. 3;

Fig. 6 is a view in vertical central-longitudinal section of the mounting-member and the parts carried thereby shown as detached from the receiver;

Fig. 7 is a top or plan view thereof with a portion of the cartridge-guide plate broken away and shown in section;

Fig. 8 is an under side view thereof;

Fig. 9 is a transverse sectional view taken on the line 9—9 of Fig. 6;

Fig. 10 is a perspective view of one of the side-plates of the magazine-throat;

Fig. 11 is a perspective view of one of the cartridge-detent springs; and

Fig. 12 is a perspective view of the cartridge-elevating plate of the magazine-throat.

The particular tubular-magazine automatic firearm herein chosen for the illustration of the present invention includes three major components, namely, a receiver 20, a barrel 21 and a stock 22.

The receiver 20 has an ejection-opening 20a and is cylindrically contoured exteriorly and has its forward end interiorly threaded for the threaded connection of the exteriorly threaded rear portion of the barrel 21, which latter has a cartridge-chamber 21a. Extending substantially throughout its length, the receiver 20 is formed with a downwardly-opening bolt-receiving chamber 23 having its upper half cylindrically contoured to conform to the similarly-contoured upper half of a reciprocating breech-bolt generally designated by the reference character 24. The said breech-bolt 24 is retained in place in the bolt-receiving chamber 23 in the receiver 20 against downward displacement therefrom, by a bar-like mounting-member generally designated by the reference character 25. The said mounting-member projects slightly upwardly into the lower portion of the bolt-receiving chamber 23 in the said receiver 20, as will be particularly well observable by reference to Figs. 4 and 5.

The bar-like mounting-member 25 above referred to, includes two substantially-corresponding parallel side-plates 26 and 27 which are laterally spaced from each other to provide a central longitudinal and vertical channel 28, by a rear spacing-block 29 and a front spacing-block 30, as is shown in Figs. 6 to 9 inclusive.

The upper portion of the rear spacing-block 29 projects above the upper surface of the side-

plates 26 and 27 of the mounting-member 25, to form a head 31 which conforms in cross-sectional form to the transverse form of the bolt-receiving chamber 23 in the receiver 20. The head 31 of the rear spacing-block 29 is formed with a rearwardly-projecting coupling-extension 32 which abuts against the forward face of the rear-wall 33 of the receiver 20 and overhangs a forwardly-extending coupling-lip 34 projecting forwardly from the lower portion of the said rear-wall 33. As thus arranged, the said coupling-extension 32 and the coupling-lip 34 serve to normally prevent the downward movement of the rear portion of the mounting-member 25 with respect to the bolt-receiving chamber 23 in the receiver 20.

Projecting rearwardly from the rear spacing-block 29 of the mounting-member 25 at the lower end thereof, is a coupling-lip 35 which is adapted to extend over a coupling-pin 36 extending transversely across the rear portion of a longitudinally-extending upwardly-opening recess 37 formed in the stock 22 before referred to. The said coupling-pin 36 thus forms a permanent feature of the stock 22.

To couple the forward portion of the bar-like mounting-member 23 to the assembly comprising the receiver 20 and the barrel 21, the front spacing-block 30 is formed with a forwardly-opening recess or coupling-socket 38 (Fig. 2) which is adapted to receive the cylindrically-contoured rear end 39 of a coupling-screw 40. The said coupling-screw 40 is threadedly mounted in a block-like stock-attaching lug 41 depending from the rear portion of the barrel 21 and fixedly attached thereto by means of a dovetail connection 42. The said stock-attaching lug 41 has threaded into it the threaded upper end of a stock-attaching screw 43 which extends upwardly from the under face of the stock 22 through an escutcheon 44 mounted in the said stock 22, and serves to secure the forward portion of the said stock to the barrel 21 and hence to the receiver 20 and its associated parts.

The receiver 20, barrel 21 and mounting-member 25 are so organized, as will be seen from the foregoing, as to constitute an assembly which may be separated as such from the stock 22. The parts 20, 21 and 25 may therefore be termed a "barrel-unit."

The breech-bolt 24 is provided with a longitudinal passage 45 in which reciprocates a firing-plunger or member 46 formed at its forward end with a firing-point 47 adapted to impinge against and fire a cartridge in the cartridge-chamber of the barrel 21 in the usual manner of firearms. In its upper rear portion the firing-plunger 46 is formed with a forwardly-facing cocking-abutment 48 which is releasably engaged by a sear-nose 49 located at the forward end of a sear 50. The said sear is mounted for pivotal movement upon a transverse pin 51 mounted in the head 31 of the rear spacing-block 29. The rearwardly-projecting portion of the sear 50 is pressed upwardly by a helical sear-spring 52, as shown in Fig. 6.

Intermediate the sear-nose 49 and the pin 51, the sear 50 is formed with a downwardly-facing actuating-abutment 53 which is adapted to be engaged by the upper end of the body-portion 54 of a transmitting-member generally designated by the reference character 55. The said transmitting-member 55 is pressed downwardly by a spring 55a and also includes a forwardly-extending finger 56 having its forward

end beveled to provide a forwardly- and upwardly-sloping cam-surface 57 which is engageable by a similarly-sloping disconnecting-cam 58 formed at the rear end of a clearance-passage 59 formed in a lug 60 depending from the rear end of the breech-bolt 24.

The transmitting-member 55 is mounted with capacity for both vertical reciprocating movement and rocking movement in the rear spacing-block 29 by means of a pin 61 mounted in the said spacing-block and extending through a vertical-slot 62 in the lower portion of the body-portion 54 of the said transmitting-member, as is shown in Fig. 6. The under edge of the body-portion 54 of the transmitting-member 55 is adapted to be engaged and lifted by the upper end of a trigger generally designated by the reference character 63 and mounted for pivotal movement upon a transverse pin 64 mounted in the stock 22. The said trigger is formed with a tubular-portion 65 through which a tubular-magazine housing 66 extends at an upwardly- and forwardly-sloping angle. The said tubular-magazine housing is mounted in the stock 22 and houses a magazine-tube 67 which has a helical magazine-spring 68 (Fig. 2) pressing forwardly upon a cartridge-follower 69 which, in turn, presses forwardly upon the rearmost one of a column of cartridges which may be located in the magazine-tube 67 and also such of those cartridges as may be in process of being fed to the cartridge-chamber of the arm as exemplified by the cartridges 70 and 71 shown in Figs. 2 and 3.

Returning now to the breech-bolt 24 and the firing-plunger 46 which it carries, it will be noted by reference to Fig. 2 that the said firing-plunger is formed with an axial rearwardly-opening bore 72 which receives the forward portion of a helical firing-spring 73 thrusting at its forward end against the end-wall of the bore 72 in the said firing-plunger. At its rear end the firing-spring 73 encircles a spring-guiding plunger 74 which, in turn, is seated against the forward face of the head 31 of the rear spacing-block 29, and which is adapted to be telescopically received in the bore 72 in the firing-plunger 46.

For the purpose of yieldingly urging the breech-bolt 24 into its breech-closing position, a helical breech-closing spring 75 is provided which presses at its forward end against the rear face of the breech-bolt 24. The said breech-closing spring 75 encircles a spring-guiding plunger 76 (Fig. 2) which is pressed rearwardly against the forward face of the head 31 of the rear spacing-block 29.

To provide for locking the transmitting-member 55 against upward movement to operate the sear 50 and thus release the firing-plunger 46, a safety lock is provided which comprises a cylindrical stem 77 and a fingerpiece 78 (Figs. 1, 2 and 3) riveted thereto. The said stem 77 extends transversely across the mounting-member 25 and is journaled therein for oscillating movement while the fingerpiece 78 extends above the adjacent upper portion of the stock 22 and is accommodated in a shallow clearance-notch (Fig. 1) 79 formed in the side-wall of the receiver 20 adjacent the rear end thereof. At a point in line with the body-portion 54 of the transmitting-member 55, the stem 77 is formed with a clearance-notch 80 (Fig. 6) which, when in the position in which it is shown by full lines in Fig. 6, provides clearance for the vertical movement of the body-portion 54 of the trans-

mitting-member 55 with the result that the stem 71 under these conditions does not in any way interfere with the free action of the said transmitting-member. When, however, the stem 71 is turned so that its clearance-notch 80 is inclined into the position indicated by broken lines 81 in Fig. 6, a portion of the said stem 71 will be projected into the path of movement of an arcuate stop-shoulder 82 formed upon the body-portion 54 of the transmitting-member 55, to thus prevent the said transmitting-member from being lifted by the trigger 63. In this manner the firearm is rendered safe since it cannot be discharged under the conditions just referred to.

Installed in the forward portion of the channel 28 of the mounting-member 25 is a group of parts constituting a "magazine throat" which will now be described in detail.

The magazine throat above referred to includes two complementary side-plates 83 and 84 extending longitudinally of the channel 28 in the mounting-member 25 and respectively located against the inner faces of the side-plates 26 and 27 of the said mounting-member as is especially well shown in Figs. 7, 8 and 9. Each of the side-plates 83 and 84 is diagonally sheared to provide an upwardly- and forwardly-sloping cartridge-elevating cam-surface 85 for the purpose as will more fully hereinafter appear.

Forwardly of its cam-surface 85, each of the side-plates 83 and 84 referred to, is formed with an in-struck rib 86 extending vertically throughout the whole width of the side-plate of which it forms a part and resulting in the formation in the outer face of each of the said side-plates of a vertical channel receiving a cartridge-detent spring 87. Each cartridge-detent spring 87 (of which there are two—one for each side-plate) is provided at its upper end with an inwardly-projecting cartridge-detent finger 88 projecting inwardly through a clearance-notch 89 formed in the upper edge of the complementary rib 86. The lower end of each of the cartridge-detent springs 87 is formed with an L-shaped retaining-finger 90, the horizontal portion of which is accommodated in a clearance-notch 91 one of which is formed in the lower edge of each of the ribs 86, as shown particularly well in Fig. 10.

Rigidly mounted intermediate the upper rear portions of the respective side-plates 83 and 84, is a cutoff-carrier 92 formed of sheet metal bent transversely into inverted U-shaped form. The said cut-off carrier 92 accommodates a pivotal cartridge-cutoff 93 which is pivotally connected at its rear end to the said carrier 92 by means of a transverse pin 94.

Extending parallel with and located laterally intermediate the side-plates 83 and 84 is a cartridge-elevating plate 95 of substantially the shape of a right-angle triangle and having its upper face or edge sloping upwardly and forwardly away from the open end of the magazine-tube 67 in substantial parallelism therewith. The said cartridge-elevating plate 95 is held in spaced relationship midway between the side-plates 83 and 84 by means of spacing-collars 96 through which extend pins 97 also extending through the said plate 95, the side-plates 83 and 84 as well as the side-plates 26 and 27 of the mounting-member 25.

As a result of the spacing between the side-plates 83 and 84 and the cartridge-elevating plate 95, two vertically-extending vent-passages 98—99 are provided for permitting the escape of gases downwardly through a vent-passage 99

formed in the stock 22 centrally in line with and beneath the mounting-member 25, as is shown especially well in Figs. 2, 3, 4 and 5, all for the purpose as will hereinafter appear.

5 Returning now to the cartridge-cutoff 93, it will be noted that the same is formed at its forward end with an actuating-nose 100 which is adapted to project upwardly through a clearance-opening 101 in the cutoff-carrier 92 for engagement with the under side of the breech-bolt 24 and for entry into a clearance-notch 102 formed in the under side of the breech-bolt, as shown. The cartridge-cutoff 93 is also formed on its under side with a downwardly-projecting cartridge-stopping finger 103 which is adapted to be engaged by the forward face of the rims or heads 104 of the cartridges 70 and 71, as well as of such other cartridges as may be included in a column of cartridges, as the same sequentially 15 emerge from the magazine-tube 67, all in a manner as will more fully hereinafter appear.

The left or outer face of the side-plate 27 of the mounting-member 25 is formed at its forward end with a vertically-extending groove 105 20 in which is installed a cartridge-guiding plate 106 having an inwardly-turned flange 107 terminating at its rear end in an ejecting-finger 108.

For the purpose of making clear the operation of the tubular-magazine automatic firearm herein chosen for the illustration of the present invention, let it be assumed that the breech-bolt 24 is in its breech-closing position and that the cartridge 109 in the cartridge-chamber 21a of the barrel 21 has just been struck by the firing-point 35 41, as is shown in Fig. 2, and that the said cartridge 109 is about to discharge.

The explosion of the cartridge 109 will move the breech-bolt 24 rearwardly and also shift certain of the other features of the firearm into the 40 positions in which they are shown in Fig. 3 of the accompanying drawings.

As the breech-bolt 24 moves rearwardly, the just-fired cartridge 109 will be withdrawn from the cartridge-chamber 21a of the barrel 21 and 45 will be brought into engagement with the ejecting-finger 108 and will thereby be ejected laterally outwardly through the ejection-opening 20a in the receiver 20 (Fig. 1).

Inasmuch as the just-fired cartridge has supplied the energy to throw back the breech-bolt 24, its retraction from the cartridge-chamber 21a will be so rapid as to permit some of the gases and residue to blow back into the space intermediate the rear end of the barrel 21 and the 55 forward face of the breech-bolt 24. This gas and attendant residue will, however, be permitted to so freely escape downwardly through the vent-passages 98—99 in the fore-portion of the mounting-member 25 and downwardly through the vent-passage 99 in the stock 22 as to effectively preclude the forcing of such gases and residue into the open end of the magazine-tube 67, thus avoiding one of the major drawbacks to 60 automatic firearms.

65 As soon as the breech-bolt 24, in its rearward travel, rides rearwardly clear of the cartridge 71, both of the cartridges 70 and 71 will move forwardly under the urge of the magazine-spring 68 until the rim 104 of the cartridge 70 comes 70 into engagement with the cartridge-stopping finger 103 of the cartridge-cutoff 93, whereupon the forward movement of the cartridges will cease, since the said cartridge-cutoff 93 is now held against upward swinging movement of its forward end by the engagement of its actuating-

nose 100 with the under face of the breech-bolt 24, as is shown in Fig. 3. As the cartridge 71 is moved forwardly as just described, it will also move upwardly in an inclined path, owing to the riding of its head or rim 104 along the inclined cam-surfaces 85—85 of the respective side-plates 83 and 84 and will force the cartridge-detent fingers 88—88 apart. Simultaneously with the riding of the rim or head 104 of the cartridge 71 as just described, the bullet-end of the cartridge will ride up the incline provided by the upper edge of the cartridge-elevating plate 95.

From the foregoing description of the movement of the foremost one of the column of cartridges, it will be seen that the cartridge 71, as well as each of the following cartridges in sequence, will be elevated by elements acting at two spaced-apart points, so as to always occupy a position substantially parallel with the axis of the breech-bolt 24.

As thus elevated, the cartridge 71 is in position to be engaged by the front face of the breech-bolt 24 when the said breech-bolt returns from the position in which it is shown in Fig. 3 into its breech-closing position as shown in Fig. 2. When the breech-bolt moves forwardly, as just referred to, the cartridge 71 will be further elevated by the coincidental action of both the cartridge-elevating cam-surfaces 85—85 and the upper edge of the cartridge-elevating plate 95 and will be ultimately seated in the cartridge-chamber 21a of the barrel 21, preparatory to the next discharge of the firearm.

While the foremost cartridge 71 is being introduced into the cartridge-chamber 21a, and until the same is substantially fully seated, the cartridge 70 will be restrained by the cartridge-cutoff 93 from moving forwardly beyond the position in which it is shown in Fig. 3 and will thus be restrained against moving into a position which might cause a jam. As soon, however, as the breech-bolt 24 reaches substantially its full breech-closing position, the clearance-notch 102 in the under face of the breech-bolt 24 will come into registration with the actuating-nose 100 of the cartridge-cutoff, thus releasing the latter from restraint and permitting the magazine-spring 68 to force the cartridge 70 into the position formerly occupied by the cartridge 71 in Fig. 2 of the drawings.

It will be understood from the foregoing that when the breech-bolt is thrown backwardly by the discharge of a given cartridge, the cocking-abutment 48 of the firing-plunger 46 will be moved to the rear of the sear-nose 49, as is shown in Fig. 3, and upon the return of the breech-bolt to its breech-closing position, the said firing-plunger will be restrained in its cocked position by the sear-nose 49 until such time as the trigger 63 is actuated.

Should it be desired, for any reason, to lock the mechanism of the firearm so that the firing-plunger 46 cannot be released by a pull upon the trigger 63, the finger-piece 78 may be swung into the position in which it is indicated by broken lines in Fig. 1, to thus turn the stem 77 so that its clearance-notch 80 is turned into the position in which it is indicated by broken lines in Fig. 6. In this latter position, the stem 77 is thus interposed in the path of movement of the transmitting-member 55 and a pull upon the trigger 63 under these circumstances will merely seat the stop-shoulder 82 of the said transmitting-member against the said stem 77.

The invention may be carried out in other

specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A tubular-magazine automatic firearm including in combination: a barrel; a receiver-unit extending rearwardly from the said barrel and having a downwardly-extending passage therein; a breech-bolt reciprocating in the said receiver-unit; a stock associated with the said barrel and receiver and extending rearwardly beyond the latter; cartridge-elevating means located beneath the said breech-bolt in the downwardly-extending passage in the said receiver-unit, the said cartridge-elevating means comprising two vertical side-plates extending substantially parallel with each other and spaced laterally from each other in a direction transverse of the firearm-structure and each having on its inner face a forwardly-and-upwardly-inclined cartridge-elevating surface positioned to be engaged by the rim of a cartridge, a cartridge-elevating plate having a forwardly-and-upwardly-inclined upper edge and spaced intermediate the two said side-plates, and spacing-means holding the said cartridge-elevating plate in substantial parallelism with the two said side-plates and spaced away from the respective inner faces of each thereof; and a tubular magazine located in the portion of the said stock to the rear of the said receiver and having a cartridge-delivery opening adjacent its forward end positioned to deliver cartridges to the space between the two said side-plates of the said cartridge-elevating means and upon the upper surface of the cartridge-elevating plate thereof.

2. A tubular-magazine automatic firearm including in combination: a barrel; a receiver-unit extending rearwardly from the said barrel and having a downwardly-extending passage therein; a breech-bolt reciprocating in the said receiver-unit; a stock associated with the said barrel and receiver and extending rearwardly beyond the latter; cartridge-elevating means located beneath the said breech-bolt in the downwardly-extending passage in the said receiver-unit, the said cartridge-elevating means comprising two vertical side-plates extending substantially parallel with each other and spaced laterally from each other in a direction transverse of the firearm-structure and each pressed outwardly intermediate its respective opposite ends to provide a forwardly-and-upwardly-inclined cartridge-elevating channel positioned to receive the rim of a cartridge, a cartridge-elevating plate having a forwardly-and-upwardly-inclined upper edge and spaced intermediate the two said side-plates, and spacing-means holding the said cartridge-elevating plate in substantial parallelism with the two said side-plates and spaced away from the respective inner faces of each thereof; and a tubular magazine located in the portion of the said stock to the rear of the said receiver and having a cartridge-delivery opening adjacent its forward end positioned to deliver cartridges to the space between the two said side-plates of the said cartridge-elevating means and upon the upper surface of the cartridge-elevating plate thereof.

3. A tubular-magazine automatic firearm including in combination: a barrel; a receiver ex-

tending rearwardly from the said barrel and having an open lower side; a mounting-member removably secured to the underside of the said receiver and comprising two laterally-spaced-apart side-plates; a breech-bolt reciprocating in the said receiver; a stock associated with the said barrel, receiver and mounting-member and extending rearwardly beyond the said receiver; cartridge-elevating means located beneath the said breech-bolt and comprising two vertical side-plates laterally spaced from each other in a direction transverse of the firearm and respectively located adjacent the inner face of one of the two side-plates of the said mounting-member, each of the side-plates of the cartridge-elevating means having on its inner face a forwardly-and-upwardly-inclined cartridge-elevating surface positioned to be engaged by the rim of a cartridge, a cartridge-elevating plate having a forwardly-and-upwardly-inclined upper edge and spaced intermediate the two said side-plates, and spacing-means holding the said cartridge-elevating plate in substantial parallelism with the two said side-plates and spaced away from the respective inner faces of each thereof; and a tubular magazine located in the portion of the said stock to the rear of the said receiver and having a cartridge-delivery opening adjacent its forward end positioned to deliver cartridges to the space between the two said side-plates of the said cartridge-elevating means and upon the upper surface of the cartridge-elevating plate thereof.

4. A tubular-magazine automatic firearm including in combination: a barrel; a receiver ex-

tending rearwardly from the said barrel and having an open lower side; a mounting-member removably secured to the underside of the said receiver and comprising two laterally-spaced-apart side-plates; a breech-bolt reciprocating in the said receiver; a stock associated with the said barrel, receiver and mounting-member and extending rearwardly beyond the said receiver; cartridge-elevating means located beneath the said breech-bolt and comprising two vertical side-plates laterally spaced from each other in a direction transverse of the firearm and respectively located adjacent the inner face of one of the two side-plates of the said mounting-member, each of the side-plates of the cartridge-elevating means being pressed outwardly intermediate its respective opposite ends to provide a forwardly-and-upwardly-inclined cartridge-elevating channel positioned to receive the rim of a cartridge, a cartridge-elevating plate having a forwardly-and-upwardly-inclined upper edge and spaced intermediate the two said side-plates, and spacing-means holding the said cartridge-elevating plate in substantial parallelism with the two said side-plates and spaced away from the respective inner faces of each thereof; and a tubular magazine located in the portion of the said stock to the rear of the said receiver and having a cartridge-delivery opening adjacent its forward end positioned to deliver cartridges to the space between the two said side-plates of the said cartridge-elevating means and upon the upper surface of the cartridge-elevating plate thereof.

35

CARL G. SWEBILIUS.
